(57) **CLAIM**

The ornamental design for a remote control, as shown.

DESCRIPTION

FIG. 1 is a front view of a remote control bearing the design;
 FIG. 2 is a back view thereof;
 FIG. 3 is a left side view thereof;
 FIG. 4 is a right side view thereof;
 FIG. 5 is a top view thereof;
 FIG. 6 is a bottom view thereof; and,
 FIG. 7 is a front-left-top perspective view thereof.
